UNITED STATES PATENT OFFICE.

JAMES PATERSON, OF LONDON, ENGLAND, ASSIGNOR OF ONE-HALF TO THE PATENT AND INDUSTRIAL DEVELOPMENT SYNDICATE, LIMITED, OF SAME PLACE.

SELF-INDICATING TARGET.

SPECIFICATION forming part of Letters Patent No. 449,270, dated March 31, 1891.

Application filed November 20, 1890. Serial No. 372,090. (No model.) Patented in England July 29, 1890, No. 11,991.

To all whom it may concern:

Be it known that I, JAMES PATERSON, of London, England, a subject of the Queen of Great Britain and Ireland, have invented an Improvement in and Relating to Self-Indicating Targets, (which has been patented to me in England under No. 11,991, dated July 29, 1889,) of which the following is a specification.

10 My invention has for its object improvements in and relative to self-indicating targets for rifle and revolver practice; and it consists in, first, the construction and arrangement of mechanism for automatically indicating when the target is struck and the value of the score obtained by the shot fired, and, secondly, in combination with said indicating mechanism, a device or appliance for obliterating the shot-marks from the face of the 20 target, all as hereinafter particularly set forth and described.

In order that my invention may be fully understood and readily carried into effect, I will now describe same with reference to the 25 accompanying drawings, in which similar letters of reference indicate like parts in all the figures.

Figure 1 is a front elevation, Fig. 2 a vertical section through line X X, Fig. 1, and 30 Fig. 3 is a plan, of the self-indicating target as constructed in accordance with this invention. Fig. 4 is a rear view to a reduced scale of the target-faces or value-plates with their spring-brackets and striker rods or pins attached; and Fig. 5 is a rear view, also to a reduced scale, of the contact-making levers and contact-springs.

Under this invention the values of that part of the target which is to be shot at are 40 each composed of one plate, the series being concentric, and, excepting the "bull's-eye" on the same plane—that is to say, the plate A, constituting the bull's-eye, has in front of it a plate B, constituting the "inner" value, concentric and in the same plane with which is or are one or more plates constituting other values. In the accompanying drawings 45 I have shown two plates C D, representing, respectively, the "magpie" and "outer" values.

The bull's-eye plate A is supported vertically on a spring-bracket a, the lower end of which is secured to the framing E, and in front of the said bull's-eye plate A the inner and other value plates B C D are similarly and separately supported, their spring-brackets being marked B' C' D' in the drawings. The inner-value plate B has an aperture b at its center equal in diameter to the desired size of the bull's-eye, while the magpie-value plate C, which is flush with the inner-value plate B, has an aperture in its center equal to the diameter or size of the inner plate, and in this aperture the latter is fitted, and the outer-value plate D is similarly formed with an aperture in its center, in which is fitted the magpie-value plate. To the value-plates I prefer to attach lugs F, into which the striker rods or pins G are screwed; but said striker rods or pins may be fitted in guides or in any other suitable manner. These lugs F extend upward to the same height, so as to carry the striking-pins all at the same level. The outer-value plate, it will be observed, will not require the lug; but a boss g may be formed directly on the plate, into which its striking rod or pin may be screwed. The rearward ends of the pins G bear against the upper extremities of levers H, centered loosely at their lower ends on a horizontal shaft or spindle I, carried in the framing E, a separate lever being provided for each value-plate of the target-face. When any one of the said value-plates is struck by a bullet, it moves rearward on its spring-brackets, thereby causing the striker rod or pin G of that plate to act on its lever H and move it through a vertical arc until the lever lies horizontally, as shown in dotted lines, Fig. 2. Each lever has a short end h projecting below its fulcrum, and when the lever is so moved the said end h comes into contact with a metal spring K, causing the upper extremity of the spring to be brought against, as also seen in dotted lines, a metal bar L, the said bar being through a wire l in communication with an electric battery. 85 90 95

The lower ends of the springs K are, as is also the metal bar L, secured to a vulcanite

block M, and they are by means of the wires k in electrical communication with an indicator situated at the firing-point and having separate disks to indicate the respective 5 values, one of the said disks being dropped or raised into view, according to the spring-transmitter and connections through which the current is passed. Any other suitable arrangement of electric indicator may be employed without departing from this invention.

Around the frame E, carrying the value-plates and levers, I have a vertically-sliding frame N, to which are attached cords or chains O, leading to the firing-point. Upon a bar P, 15 carried by this frame N, the levers H rest when assuming the horizontal position and making electrical contact, as above described. The front part of the sliding frame N carries a whiting-brush Q or its equivalent, which 20 dips into a box R, placed below and in front of the value-plates. The said box contains a mixture of whiting and water or equivalent material, and when the value of the shot has been indicated, as aforesaid, the sliding 25 frame N is pulled up by the marksman or attendant at the firing-point and the whiting-brush is caused to pass over the face of the target and obliterate the mark of the shot. The pulling up of the sliding frame N at the 30 same time causes the lever H, which had been dropped, to assume its vertical position and break contact of the spring-transmitter. A check-chain U may be attached to sliding frame N to limit its upward travel to the 35 amount desired.

The target-frame is supported at the desired height from the ground on standards S. The two rear ones may be conveniently of angle-iron, and will form a guide in which a guide-block T, attached to vertically-sliding frame 40 N, may be fitted for facilitating the manipulation of said sliding frame.

Having fully described my invention, what I claim, and desire to secure by Letters Patent, is—

1. A self-indicating target consisting of concentric value-plates supported by flexible pillars, each plate carrying a striker G, an unequally-pivoted contact-making lever H to each value-plate, operated by the said striker 50 on the longer arm of the said lever H, a spring-contact-making device operated by the shorter arm of the said lever H, and a sliding frame operated from the firing position to return the contact-levers to their normal position, substantially as described.

2. In combination with a self-indicating target having contact-levers H, a spring electrical contact device, and sliding frame N, the brush Q, carried by the sliding frame N, and 60 box R, into which the said brush Q dips, substantially as described.

In testimony whereof I have signed my name to this specification in the presence of two subscribing witnesses.

JAMES PATERSON.
